(57) **CLAIM**

The ornamental design for a light fixture, as shown and described.

DESCRIPTION

FIG. 1 is a perspective view of a first embodiment of a light fixture of our design.

FIG. 2 is a side view of the light fixture of FIG. 1, the other side view being a mirror image of the side view of FIG. 2.

FIG. 3 is a front view of the light fixture of FIG. 1.

FIG. 4 is a back view of the light fixture of FIG. 1.

FIG. 5 is a top view of the light fixture of FIG. 1.

FIG. 6 is a bottom view of the light fixture of FIG. 1.

FIG. 7 is a perspective view of a second embodiment of a light fixture of our design.

FIG. 8 is a side view of the light fixture of FIG. 7, the other side view being a mirror image of the side view of FIG. 8.

FIG. 9 is a front view of the light fixture of FIG. 7.

FIG. 10 is a back view of the light fixture of FIG. 7.

FIG. 11 is a top view of the light fixture of FIG. 7; and,

FIG. 12 is a bottom view of the light fixture of FIG. 7.

The portion in phantom line and the area circumscribed thereby of each embodiment of the light fixture is not part of the design.
